UNITED STATES PATENT OFFICE.

WALTER J. ROWLEY, OF ALLEGHENY, PENNSYLVANIA.

TROLLEY.

SPECIFICATION forming part of Letters Patent No. 748,422, dated December 29, 1903.

Application filed May 7, 1903. Serial No. 156,095. (No model.)

To all whom it may concern:

Be it known that I, WALTER J. ROWLEY, a citizen of the United States of America, residing at Allegheny, in the county of Allegheny and State of Pennsylvania, have invented certain new and useful Improvements in Trolleys, of which the following is a specification, reference being had therein to the accompanying drawings.

This invention relates to certain new and useful improvements in trolleys, and has for its main object to provide novel and effective means for preventing the trolley-wheel from becoming accidentally disengaged from the trolley-wire.

Briefly described, the invention comprises a harp, which is provided with two vertically-disposed arms extending above the trolley-wheel that is journaled in the harp, and in the upper end of each of these vertical arms is pivoted a dog, which dogs act as guards to retain the wheel in engagement with the wire, the guards being held in normal position by means of springs carried by the arms and engaging the dogs.

In describing the invention in detail reference will be had to the accompanying drawings, forming a part of this application and wherein like numerals of reference will be employed for designating like parts throughout the different views of the drawings, in which—

Figure 1 is a side elevation of a trolley constructed in accordance with my invention, the trolley-pole broken away. Fig. 2 is a rear elevation of the same; and Fig. 3 is a top plan view, the harp and trolley-wheel being partly broken away.

In the accompanying drawings, 1 indicates the prongs of the harp, which latter is suitably attached to the trolley-pole 2. Between the prongs of the harp on the axle or shaft 3 is mounted the ordinary trolley-wheel 4. Each prong carries an upwardly-extending vertically-disposed arm 5, in which, near its upper end, is a transverse slot 6, and pivotally mounted in these slots of the vertically-disposed arms are guards 7, which are engaged by and are under the tension of springs 8, attached to the rear face of the vertically-disposed arms 5.

The spring-pressed guards 7 extend beyond the sides of the harp and have attached thereto cords or ropes 9, connected to a common rope or cord 10. The ropes or cords 9 are passed through eyes 11, carried by the vertically-disposed arms 5 in alinement with the guards 7, whereby when a downward pull is made on the cord or rope 10 the guards 7 will be spread in order to permit the placing of the trolley-wheel into engagement with the wire or the removal of the said wheel from the wire. I may also employ eyes 12 near the lower end of the harp through which the cords 9 are passed in order that the pull against the eyes 11 may not be so direct as if the cords hung down vertically.

When the guards come into engagement with a switch or hanger, the same will readily spread apart, so as to permit the passage of the trolley, and as soon as said switch or hanger has been passed the springs will return the guards to their normal position, whereby to prevent accidental disengagement of the trolley-wheel from the wire. The side walls of the slots 6 may be made curved, as seen by dotted lines in Fig. 3, whereby to give sufficient movement to the guards when they are actuated.

While I have herein shown and described the invention in detail as it is practiced by me, yet it will be evident that various changes may be made in the details of construction without departing from the general spirit of my invention.

Having fully described my invention, what I claim as new, and desire to secure by Letters Patent, is—

In a trolley, the combination with the harp each prong of which carries a vertically-disposed arm provided near its upper end with a transverse slot, of guards pivoted in said slots, springs connected to the vertical arms and engaging said guards, and cords connected to said guards for actuating the same,

as and for the purpose described.

In testimony whereof I affix my signature in the presence of two witnesses.

WALTER J. ROWLEY.
